DRINKING TUBE AND METHOD OF
MANUFACTURING SAME

Karl E. Garling, Newark, N. J., assignor to Soda
Straw Manufacturing Corporation, Newark,
N. J., a corporation of New Jersey

Application December 5, 1930, Serial No. 500,157

3 Claims. (Cl. 93—94)

Among the principal objects which the present invention has in view are: To temporarily unite the paper members forming such tubes preparatory to treating them with paraffine or similar material; to manufacture tubes from paper strips disposed in laminated relation, the layers being temporarily partially united by means of a suitable adhesive; to unite adhesively the layers of paper above referred to by means of adhesive 5 disposed in limited areas between the strips; to manufacture tubes from strips of paper superposed in laminations by impregnating same with paraffine or other water resisting material, after first temporarily uniting the same by means of an 10 adhesive disposed in limited areas.

Drawing

Figure 1 is a side view of a tube of the character mentioned, its paper elements being partially 20 segregated to show the condition of said elements prior to being rolled as a straw.

Figure 2 is a side view of a completed tube.

Description

25 The present invention has especially in view the manufacture of drinking tubes or sippers from paper for use in soda water dispensing establishments or establishments of a similar character. A difficulty has heretofore existed in maintaining 30 the laminations of paper together, when so employed during the first moments of service in liquid. The method which has heretofore existed has consisted in first rolling on a mandrel, in spiral shape, two or more layers of relatively narrow strips of paper superimposed, one upon the other. The laminations thus arranged have been 35 heretofore secured by suitable adhesive, such as glue. It has been found that the laminations thus secured, separate in part or wholly.

40 It has been found, also, that a certain proportion of the tubes which have avoided, or failed to separate as above set forth will, when inserted in liquid, open, or separate, within a few minutes. Both of the above objections are disastrous to 45 business devoted to the manufacture and sale of these tubes and to avoid these objections is the principal purpose of the present invention.

To accomplish the above stated object, I provide the upper and outer strip 9 with narrow continuous areas 10 of a suitable adhesive so arranged as to leave a central continuous area 11 without adhesive. In the manufacture of these tubes, the outer strip 9 is superimposed upon the 50 strip 12, preferably arranged so that the juxtaposed edges of the strip 12 when spirally wound align with the area 11 of the strip 9.

The adhesive on the areas 10 is sufficient to hold the strips 9 and 12 in shape as formed on and delivered by the machines employed in their manufacture. Subsequently, the tubes so formed are submitted to a bath of liquid paraffine maintained at a suitable temperature. The paraffine is employed to resist the action of liquids. It has been found that paraffine thus employed will 10 permeate and become a part of the structure of the strips 9 and 12 and will thoroughly and efficiently unite the same, particularly where the adhesive areas 10 do not exist. The tendency to separate at these areas is counteracted by the 15 efficient junction of the strips registering with the central area 11.

It may here be stated that liquid paraffin will 20 permeate or pass through paper, but will not pass through an adhesive. By the present invention, the paraffin accordingly obtains an adhesion, impermeable to water, along the central continuous area 11, and the juxtaposed edges of the strip 12, and this adhesion is therefore unaffected 25 by long presence of the finished article in water or the like in use. Most adhesives suitable for use along the continuous edge areas 10 will dissolve in water after a few minutes, but since the straw is, according to my invention, sealed by another spiral adhesion, namely the paraffin 30 at the central continuous area 11, the same retains its form and efficiency almost indefinitely. It is however, essential that this central area be continuous.

35 By the method of constructing the tubes as above set forth, an improved article is produced in which the objections above noted are obviated.

I claim:

1. A tube as characterized constructed of laminated paper strips disposed as inner and outer strips, the outer strip overlapping the edges of the inner strip, means for uniting said strips, said means embodying an adhesive disposed on said outer strip adjacent and uninterruptedly along the edges thereof and arranged to provide a continuous uncoated area at the longitudinal center of said outer strip and in line with the abutted edges of said inner strip, and means for uniting said edges of the inner strip and the uncoated central area of said outer strip, said means embodying a coating of material impervious to water, said material entering between the abutted edges of the inner strip and under said uncoated area of said outer strip to adhere the same.

2. A tube as characterized constructed of lami-

- nated paper strips disposed as inner and outer strips, the outer strip overlapping the edges of the inner strip means for uniting said strips, said means embodying adhesive disposed on said outer strip in 5 restricted areas adjacent and uninterrupted along the edges thereof to provide a continuous uncoated area at the center of said outer strip in line with the abutted edges of said inner strip, and means for uniting said abutted edges of the 10 inner strip and the uncoated central area of said outer strip, said means embodying molten paraffine introduced between the edges of said inner strip and under the uncoated area of said outer strip.
- 15 3. A method of forming a tube as characterized constructed of paper strips disposed in laminated position, said method consisting in preparing a plurality of narrow strips of paper to be spirally

wound one upon the other, said preparation embodying adding to the outer strip a suitable adhesive pervious to water in restricted areas adjacent and uninterrupted along the edges of said strip by preventing said adhesive covering a 5 continuous longitudinal central area of said strip, then disposing said strips while winding same so that said uncoated central area is disposed above the abutted edges of the inner strip, then immersing the tube so formed in heated paraffine 10 to coat the inside of said inner strip and the space between the edges of said inner strip and the uncoated central area of said outer strip, whereby water is prevented from entering between said edges of said inner strip and said outer 15 strip.

KARL E. GARLING.
